UNITED STATES PATENT OFFICE.

ALBERT S. NEWTON, OF PROVIDENCE, RHODE ISLAND.

WASTE-TRAP.

Specification of Letters Patent. Patented July 27, 1920.

1,347,551.

Application filed March 1, 1920. Serial No. 362,459.

To all whom it may concern:

Be it known that I, ALBERT S. NEWTON, a citizen of the United States, residing at Providence, in the county of Providence and State of Rhode Island, have invented certain new and useful Improvements in Waste-Traps, of which the following is a specification.

My invention relates to waste traps and has for its primary objects the utilization of the waste water in resealing, to efficiently 10 guide the water to the upper baffle plate, and by a means which will not accumulate grease; and to attain these ends in a structure of increased simplicity, and efficiency.

My invention, therefore, consists in the means for attaining the ends hereinabove set forth.

In the accompanying drawings which 20 form a part of this specification,

Figure 1 is a central vertical section of my trap.

Fig. 2, a section of the same on line x , x , of Fig. 1, and

Fig. 3, a vertical section of a modification.

Similar reference numerals indicate similar parts throughout the drawings.

The body of my trap consists in the present instance of a substantially cylindrical side wall 4 having a retracted rounded upper portion 5 merging in an upwardly and outwardly directed neck or pipe 6 having a threaded connection 8 with a tube 9 which together with the neck constitutes the outlet 35 of the trap.

The lower end of the body is open and has a thread 11 engageable with an external 40 thread 12 on a disk 13 provided with a peripheral extension 14 adapted to abut against the body. The bottom face of the disk has a squared operating projection 16, and fast in the upper face of the disk is a post having a solid lower portion 18 and a tubular upper portion 19 provided with 45 a series of staggered perforations 20 in its wall 21 opening into its bore 22. The wall 21 at its top expands to form an integral outwardly and downwardly flaring abutment 24 or baffle plate forming an annular 50 space.

Near its bottom the wall or body 4 is provided with a hollow projection 26 extending outwardly and upwardly, having a threaded connection as at 27 with a pipe 28, which 55 combined with the extension constitutes the inlet of the trap.

Below the baffle member 24 integral with

the wall 4 is a downwardly inclined annular flange or deflecting plate 30.

The water enters through the inlet and leaves the trap through the outlet. In its course it is by the portion 30 so deflected that a portion thereof is impeded and thrown downwardly by the plate 24, while some of the remainder passes through the outlet, and the remainder falls down into the tubular part of the baffle plate and post, whence it passes out through the perforations and assists to reseal the trap.

The grease is carried by the top of the water. The upper surface of the water as soon as it reaches the lower edge of plate 24 cannot rise any higher therein because of the air in the annular space. Hence the grease cannot lodge in such space. The same is true of the downwardly directed deflecting plate 30, which also forms an inclosed annular chamber.

If preferred the body 4 need not be cylindrical throughout its length. A more economic form of body construction consists, as shown in Fig. 3, of a lower cylindrical portion 32 of less diameter than the body 4 having a swelled upper portion 34 around the baffle plate.

I claim:

1. In a waste trap, a body, an inlet pipe near the bottom of the body, an outlet pipe in the upper portion of the body, and a post fast to the bottom of the body comprising a solid lower portion, a tubular upper portion provided with perforations, and an open baffle upon the top of the tubular portion between the inlet pipe and outlet pipe.

2. In a waste trap, a body provided with a contracted upper portion, and with a contracted intermediate portion, an outlet pipe in the contracted upper portion, an inlet pipe in the lower portion of the body, a vertical post fast to the bottom of the body, and a baffle plate on the post intermediate the retracted portions.

3. In a waste trap, a body, an inlet pipe near the bottom of the body, an outlet pipe in the upper portion of the body, a post on the bottom of the body, a baffle on the post between the inlet pipe and outlet pipe, and a downwardly inclined annular deflecting plate on the body below the baffle plate.

In testimony whereof I have affixed my signature.

ALBERT S. NEWTON,
